US00D939855S

(12) **United States Design Patent** (10) **Patent No.:** **US D939,855 S**
(45) **Date of Patent:** **** Jan. 4, 2022**

(54) **PAPER ROLL**

(71) Applicant: **Hagleitner Hygiene International GmbH**, Maishofen (AT)
(72) Inventor: **Hans Georg Hagleitner**, Zell am See (AT)
(73) Assignee: **Hagleitner Hygiene International GmbH**, Maishofen (AT)
(**) Term: **15 Years**
(21) Appl. No.: **35/509,680**

(22) Filed: **Dec. 20, 2019**

(80) **Hague Agreement Data**

Int. Filing Date: **Dec. 20, 2019**
Int. Reg. No.: **DM/206714**
Int. Reg. Date: **Dec. 20, 2019**
Int. Reg. Pub. Date: **Jun. 26, 2020**

(30) **Foreign Application Priority Data**

Jun. 26, 2019 (EM) 6592960
(51) **LOC (13) Cl.** **23-02**
(52) **U.S. Cl.**
USPC **D6/518**
CPC **A47K 10/16** (2013.01)
(58) **Field of Classification Search**
USPC D6/518-523; 206/389, 391; 211/13.1,
211/59.1, 45, 890.1; 242/599.1, 599.3,

Primary Examiner — Richard E Chilcot

(74) *Attorney, Agent, or Firm* — Laurence A. Greenberg;
Werner H. Stemmer; Ralph E. Locher

(57) **CLAIM**

The ornamental design for a paper roll, as shown and described.

DESCRIPTION

1. Paper roll
1.1 is a perspective view of the paper roll, showing my new design;
1.2 is a front view thereof;
1.3 is a back view thereof;
1.4 is a top view thereof;
1.5 is a bottom view thereof;
1.6 is a left side view thereof;
1.7 is a right side view thereof;
1.8 is a perspective view thereof;
1.9 is a front view thereof;
1.10 is a back view thereof;
1.11 is a top view thereof;
1.12 is a bottom view thereof;
1.13 is a left side view thereof; and
1.14 is a right side view thereof

1 Claim, 14 Drawing Sheets
